UNITED STATES PATENT OFFICE

DAVID MCCHESNEY, OF KIRKLAND LAKE, ONTARIO, CANADA

EXTERIOR CORNER CONNECTION FOR WALL BOARDS

Application filed May 31, 1930. Serial No. 458,507.

My invention relates to improvements in exterior corner connections for wall boards, which will render the joint invisible and, at the same time, reinforce the corner's apex so that there is no danger of the edge becoming chipped or broken, and it consists essentially of the arrangement and construction of parts as hereinafter more particularly explained.

10 Fig. 1 is a sectional plan view showing my corner connection.

Fig. 2 is a perspective detail of a fragmentary portion of the connecting plate.

In the drawings like characters of reference indicate corresponding parts in each figure.

15 1 is a vertical scantling forming the corner post of the frame work. 2 and 3 are wall boards placed against each outer face of the post 1 so that their end faces are disposed at right angles one to the other. The outer face of the boards 2 and 3 are provided with edge recesses 2^x and 3^x.

20 4 and 5 are arms of a corner plate set at right angles one to the other and counter sunk within the recesses 2^x and 3^x, the arms 4 and 5 being connected together at the apex of the angle formed thereby by a bead 6 extending longitudinally of the plate. The outer 25 periphery of the bead 6 is in horizontal alignment with the outer face of the wall boards 2 and 3 so that when the recesses 2^x and 3^x are provided with a filling and 2° and 3° a flush surface is formed extending from the face 30 of the wall board to the extreme corner formed by the arms of the plates 4 and 5 and the bead 6.

35 The arms 4 and 5 of the plate are connected to the corner post 1 by nails 7 and 8 which extend through perforations 4^x and 5^x in the arms 4 and 5 through the recessed portion of the wall boards 2 and 3 into the post 1. Large perforations 9 and 10 are also formed in the 40 arms 4 and 5 respectively adjacent to the bead 6 and opposite the hollow place formed between the wall board ends and through which the filling 2° and 3° is forced in order to key it as indicated at 11 and 12. The 45 remaining holes 5 which are not utilized by

the securing nails 7 and 8 also aid to key the filler in place.

From this description it will be seen that I have devised a very simple construction whereby a joint is formed to provide a flush surface around an exterior corner in such a way that the apex of the corner is reinforced so that it cannot possibly be broken or chipped.

What I claim as my invention is:

1. In a wall board corner connection, the combination with a corner post, of a wall board having a recessed outer edge placed against each outer face of a corner post, an angle plate the arms of which are counter sunk in the recesses, securing means extending through the arms of the plate, recessed portions of the wall board and into the post, and a plastic filler for the recess covering the arms of the plate.

2. In a wall board corner connection, the combination with a corner post, of a wall board having a recessed outer edge placed against each outer face of a corner post, an angle plate the arms of which are counter sunk in the recesses, securing means extending through the arms of the plate, recessed portions of the wall board and into the post, and a bead formed integral with the arms of the plate the exterior periphery of which is flush with the surface of the wall board, and a filler for the recess the outer face of which is flush with the surface of the wall board and the exterior periphery of the bead.

DAVID MCCHESNEY.
